[57] CLAIM

The ornamental design for a dinner plate or the like, substantially as shown and described.

DESCRIPTION

FIG. 1 is a top plan view of a dinner plate or the like of conventional configuration showing my new design; FIG. 2 is an enlarged fragmentary top plan view of a section of the dinner plate or the like of FIG. 1 showing a repeat unit of my design; and FIG. 3 is an enlarged fragmentary sectional view taken along the line 3—3 of FIG. 2; the surface decoration that would be visible beyond the cut line has been omitted for ease of illustration.
